(57) **CLAIM**

The ornamental design for an injector, as shown and described.

DESCRIPTION

FIG. 1 is an isometric view of a front, top, and right side of an ornamental design for an injector in a first configuration; FIG. 2 is a front elevational view of the injector of FIG. 1; FIG. 3 is a right side elevational view of the injector of FIG. 1; FIG. 4 is a top plan view of the injector of FIG. 1; FIG. 5 is a bottom plan view of the injector of FIG. 1; FIG. 6 is an isometric view of a front, top, and right side of the injector of FIG. 1 in a second configuration; FIG. 7 is an isometric view of a front, top, and right side of the injector of FIG. 1 in a third configuration; and, FIG. 8 is an isometric view of a front, top, and right side of the injector of FIG. 1 in a fourth configuration. The dash-dash-dash lines are included for the purpose of illustrating portions of the injector that form no part of the claimed design.

1 Claim, 4 Drawing Sheets
